23 Claims. (Cl. 250—8)

1

The present invention relates to systems for printing telegraphs and particularly systems adapted for transmission of messages by means of radio.

In ordinary transmission, utilizing very short code signals, it is known that parasitic influences cause addition or suppression of signals, whereby errors in reception are produced. For instance, one letter is printed instead of another, etc.

An object of the present invention is the reduction or elimination of parasitic disturbances in the transmission of code signals by means of a printing telegram.

In brief, I accomplish this result in the following manner: Garbling of code signals due to parasitic influences is appreciably reduced by lengthening the duration of the signals while using a low resonance frequency having a large time constant. However, a disadvantage of this arrangement resides in the fact that lengthening of the duration of the signals brings about an unacceptable slow-down in transmission.

It is therefore a further object of the invention to provide means for preventing a slow-down in transmission of the code signals while permitting, nevertheless, lengthening of the duration of the signals to such a degree that garbling, due to parasitic action on the radio connection, is reduced or practically eliminated.

This result is obtained, according to certain characteristic features of the invention, in the following manner: A frequency of different modulation of a single carrier wave is assigned to each code signal and the total number of these frequencies for a code of five elements for example is six; namely, one frequency for each code signal plus one additional frequency for the signal for starting the printing telegraph at the receiving station. It thus becomes possible to transmit each code signal not just during a very short period of time, which is but a fraction of the total period of time allotted to the complete signal combination (comprising the starting signal and the following signals making up the code symbol of a particular character), but during the totality of that period of time. For instance, if the system is adapted to operate at a speed of seven characters per second or approximately 140 milli-seconds for each character, the transmission of various frequencies, including the starting signal and the code signal, will last 140 milli-seconds. Upon reception, the signals are separated by filters and act upon the respective relays which register the combinations of the code. During the next period of 140 milli-seconds, which is

2

consumed by the transmission of the next character, the registered signals of the former character set up the combination upon the receiving translator and printing takes place thereafter during transmission of the next following or a third character. Thus, the total time allotted for the transmission and printing of a character is 420 milli-seconds, of which 280 milli-seconds are used for the transmission of a second and third character which are stored by the receiving apparatus to be printed successively as following characters are received.

Inasmuch as the starting signal is sent alone, its intensity must be such that the modulation 15 of the sending station is a maximum. The signals of the code are sent in permutations of 5 in the present embodiment of the invention which contemplates a code of five elements, the intensity of each signal being such that the total of 20 five signals produces maximum modulation of the sending station. As a result, one obtains a variation of the modulation ranging from 0 to the maximum, according to the number of the marking signals of the code. Due to this arrangement, 25 it would become impossible to use devices for attenuating parasitic influences such as for instance limiting means. The present invention overcomes this drawback by sending a code signal not just by direct transmission of a frequency, 30 but by variation of this frequency which is being transmitted continuously.

Thus, during the time reserved for transmission of signals, the transmitter is modulated by the combined code frequencies f_1 , f_2 , f_3 , f_4 , and 35 f_5 , for instance. The sending of a marking signal consists in causing a slight variation of the corresponding frequency in a fractional amount thereof, for instance by slightly increasing the capacity of the resonant circuit relating thereto. Frequency f_1 becomes $f_1 - \Delta f_1$ for the sending 40 of the first code signal etc. Similarly, while awaiting the starting signal, the transmitter is modulated at the frequency f_6 and the sending of the starting signal is produced by varying the 45 frequency from f_6 to $f_6 - \Delta f_6$.

The modulation of the transmitter by means of frequencies f_1 to f_6 may be produced by any known method, for instance by means of simple modulation while transmitting a carrier and two 50 lateral bands or, preferably, by means of modulation without carrier while sending a single lateral band, or by means of frequency modulation etc.

Irrespective of the modulating method chosen, 55 after reception the frequencies f_1 to f_6 are fur-

nished by the receiver. It is possible to arbitrarily choose frequencies f_1 to f_6 according to the present invention, the frequencies assigned to the code signals should preferably be contained in an octave in order to avoid intermodulation frequencies. For example, one may use for the code signals the harmonics 11, 13, 15, 17, and 19 of such basic frequency as may be desired. For instance, 50 cycles per second would give the following frequencies: 550, 650, 750, 850 and 950. Moreover, in order to assure a more uniform filtering action, this invention also provides for the determination of each frequency in such manner that the spacing between two adjacent frequencies is a constant fraction of one of the two frequencies; with a spacing of approximately 15% of the lowest frequency, the following values are obtained: 550, 628, 722, 830 and 955.

The frequency of the starting signal, which is sent alone may be of any desired value but the same is preferably superior to the highest signalling frequency in order to prevent the harmonics from falling within the range of the code signal frequencies. In the example given above, this frequency could for instance be 1100 cycles per second.

The factor which characterizes the variation of frequencies for producing marking signals is made as small as possible in order not to render separation of frequencies difficult. With resonant circuits of good quality one may use a factor of 0.02.

The invention also provides means for producing the transmission of frequencies according to the method described above and uses a radio transmitter controlled by a printing telegraph transmitter. Moreover, the present invention uses the various frequencies obtained from the output of a radio receiver in order to operate a printing telegraph receiver.

With these and other objects in view, as will be more apparent hereinafter, the present invention is fully described in the following specification and illustrated, by way of example, in the accompanying drawings, in which—

Fig. 1 is a schematic view of a printing telegraph transmitter;

Fig. 2 shows schematically a printing telegraph receiver, designed for cooperation with radio receiving apparatus.

In the drawings, Fig. 1 illustrates the transmitter comprising five key bars 1, 2, 3, 4, 5, whose movement is controlled by keys such as 6, 7, 8, and 9. Transmitting keyboards of this type are well known in the printing telegraph art, for example, the present "Teletype" and "Creed" keyboards. The connection between the keys and the bars is conventional and not shown in the drawing. When a key is depressed, shaft 10 is connected by a clutch, not shown, to motor 11 and performs one revolution and is then stopped in well known manner by the disengaging of the clutch members. Shaft 10 carries two cams 12, 13 which operate contact springs 14 and 15, respectively. Bars 1 to 5 close combinations of contacts 16 to 20 when moved toward the right in response to the operation of any key, the combinations depending on the particular permutation of the five unit code assigned to the operated key. For the purpose of explanation it is assumed that any closed contact will cause the transmission of a marking impulse while the open contacts cause the transmission of a spacing impulse. The transmitter E produces modulation by means of oscillators O1 to O5 which are connected to contacts 14 to 20 and to one contact of spring 15, as

shown in the drawings. A sixth oscillator O6 is connected to contact 14 and to one contact of spring 15. It will be noted from the shape of cams 12 and 13 that the duration of the start signal occupies about one third of the rotary cycle of shaft 10 while the remainder of the cycle, that is, during the time cam 13 holds contact lever 15 against its upper contact, is used for the simultaneous transmission of the frequencies assigned to the particular character being transmitted. In rest position, oscillator O6 operates alone, one of its circuits being closed by contact 15a. Thus a frequency f_6 is produced and the transmitter sends a modulated wave at this frequency. When a key is depressed, the clutch, not shown, engages and shaft 10 is connected and turns, whereupon cam 12 immediately closes contact 14 which serves for changing the frequency of oscillator O6. The frequency thus becomes $f_6 - \Delta f_6$ and the transmitter sends a modulated wave at this frequency. It is this wave which serves as the starting signal. This wave is of relatively very long duration, during which time shaft 10 turns approximately 120 degrees. Thereafter cam 12 moves out of engagement with contact lever 14 removing the ground from the oscillator O6, and at the same time cam 13 acts upon spring 15 and contact 15a is opened and oscillator O6 is completely stopped, while contact 15b is closed and puts oscillators O1 and O5 into operation. The latter act upon the transmitter so as to send five frequencies simultaneously. The value of each of these frequencies depends upon the position of bars 1 to 5, that is to say opening and closing contacts 16 to 20 which, when closed, cause the frequency of the corresponding oscillator to change from f to $f - \Delta f$.

The five frequencies transmitted thus depend upon the position of the bars 1 to 5, or in other words, upon the combination of the code corresponding to the letter to be transmitted.

The simultaneous transmission of the five impulses lasts a relatively long time, that is for substantially all of the remainder of the rotary cycle of shaft 10 while the raised portion of cam 13 holds contact lever 15 against its upper contact b.

At the end of the revolution of shaft 10 contact 15b is opened and contact 15a closed. The transmitter thereupon emits the rest position wave which is modulated at a frequency f_6 , this being analogous to a constant spacing signal being sent to the line, which practice is well known in the start stop printer art. Bars 1 to 5 are then restored to rest position in the well known manner thereby opening any of the contacts 16 to 20 which may have been closed. The apparatus is thus restored to starting position and is ready again for transmitting a new character.

It should be noted that the transmitter keyboard mechanism is simpler than that used in conventional start stop systems in that no distributor is required for sending the selecting impulses in succession, because the selecting impulses are transmitted simultaneously after the start signal has been sent. Cams 12 and 13 serve to separate and time the transmission of the start impulse and the selecting impulses.

An example of a receiving circuit is schematically shown in Fig. 2.

The invention contemplates the use of a start stop receiving printer preferably of the kind known in the art as a "single magnet" printer wherein one magnet serves as a start magnet and also responds to selecting impulses received after the start impulse to control the operation of a

mechanical selector. Printers of this kind are provided with a constantly operating motor which furnishes power for the operation of the printer.

Between the motor shaft and a power shaft of the printer is a clutch whose driving and driven members are normally disengaged under control of the start magnet armature. When a start impulse is received, the start magnet operates releasing the shaft which makes one revolution and then stops on engaging the start magnet armature. The shaft remains stationary until released when the start signal for the next character is received. The power shaft usually carries or drives a mechanical distributor arrangement which cooperates with the start magnet when the latter is receiving selecting impulses to control the selecting mechanism of the printer. There are many variations of this mechanism, all of which, however, have the same general principle of operation. In this country the "Teletype" is the best known of the single magnet printers, while in Europe the "Creed" single magnet is commonly used.

It will be understood that the printer motor and the keyboard motors are controlled by suitable governors set so the motors turn at almost the same speed, that of the printer being a trifle higher to ensure that the printer motor will come to a stop with each revolution, so that when the next start signal is received, the printer motor will start off in unison with the incoming signals according to the usual practice.

In Fig. 2 of the drawings, printer motor 11 is shown as being connected to shaft 22. In actual practice, however, it will be understood that shaft 22 is connected by suitable gears to the printer power shaft, rather than directly to the motor, and in this way the magnet indicated by reference character 21 serves as a start magnet for both shafts as well as functioning as a selecting magnet for the printer. It should be kept in mind that in the present invention magnet 21 does not receive the selecting impulses directly from an incoming circuit for the reason that all selecting impulses are received simultaneously which makes it necessary to first separate the frequencies by suitable filters and register them on relays when so separated, and later by means of a cam arrangement on shaft 25 of which only those cams 29 and 30 required to control the first impulse are shown, the impulses stored on a group of relays are sent one at a time to magnet 21 via a second distributor arrangement including cam 24 and a series of contacts which separate the impulses and sends them properly timed to magnet 21, so that the latter operates at just the right time to control the respective mechanical selectors within the printer. There is no difficulty in this because shaft 22 and the printer shaft are driven from a common source of power and turning in fixed relationship with each other, and cam 24 and the contacts controlled thereby can be spaced to secure the optimum result.

As already stated, the shaft of the receiver (not shown) is adapted to make one revolution for each character. This shaft is associated with a second shaft 22 carrying two cams 23, 24 which act upon certain contact springs referred to further on. Shaft 22 in turn rotates shaft 25 by means of a reduction gear 26, 27, having a ratio of 1:2. As a result, shaft 25 makes a half revolution for each character received. Shaft 25 carries three cams 28, 29, 30 acting upon certain contact springs described below. The receiving circuit comprises resonant circuits for the selection of

frequencies, relays for the reception of signals, registering relays and switch contacts actuated by the cams as more fully described hereafter.

Radio receiver R feeds the detected modulating currents to the grid of tube 31 of low impedance, whereby a transformer 32 may be interposed for the purpose of bringing the amplitude of the currents to such a value that the tube 31 acts as a limiter. The plate is fed across a low resistance 33. A condenser 34 of great capacity connects the plate to spring 35 which is actuated by cam 23.

In rest position of the apparatus, while awaiting the starting signal, the raised portions of cam 23 push up spring 35 to close contact a. The plate circuit of tube 31 is connected to a resonant circuit closed by condenser 36 and self-inductance 37. This circuit is adjusted for resonance at the frequency $f_6 - \frac{1}{2}\Delta f_6$ and is damped as little as possible, provided that the resistance 33 is of low value and permits frequencies f_6 and $f_6 - \Delta f_6$ to pass with like efficiency. This first resonant circuit serves as a reducing filter for the starting signal. The point between the self-inductance 37 and the capacitance 36, where the supertension is produced, is connected to the grid of a second tube 38 whose plate is fed across a resistance 39 and connected by means of a condenser 40 to two spools 41, 42 serving for the excitement of the two resonant circuits 43 and 44. Circuit 43 is adjusted to a frequency slightly higher than f_6 and circuit 44 to a frequency slightly lower than $f_6 - \Delta f_6$. Both have a high coefficient of supertension and their time constant can be relatively large as compared to the duration of the starting signal.

Circuits 43 and 44 are connected, in known manner, so as to act differentially across oppositely connected rectifiers 45, 46 and resistances 47, 48 upon the polarized relay 49. Fig. 2 shows a direct connection with relay 49, however, in order to preserve the full efficiency of the resonant circuits 43, 44, provision is also made for insertion of a tube. During the waiting period, the frequency f_6 is received and the resonant circuit 43 is excited more than circuit 44. The current in polarized relay 49 has such a direction that the latter opens its contact. When frequency $f_6 - \Delta f_6$ is received, circuit 44 is more excited and relay 49, which is traversed by a current in opposite direction, closes its contact. It should be noted that the circuit arrangement according to the present invention is hardly sensitive at all to parasitic influences. If such occur, they are reduced by the first resonant circuit and act upon circuits 43 and 44 with equal intensity. As a result, the relay 49 is not affected at all.

The contact of relay 49 is connected to the electromagnet 21 by means of spring contact 50 which is actuated by the raised portions of cam 24.

As soon as the electromagnet 21 operates, the printer power shaft, not shown, and also shaft 22 starts to revolve. Cam 23 disengages from spring 35 which opens its contact a and closes its contact b. The plate of tube 31 is now connected in parallel to five resonant circuits 51, 52, 53, 54, 55, each of which circuits is adjusted for the following frequencies, respectively: $f_1 - \frac{1}{2}\Delta f_1$, $f_2 - \frac{1}{2}\Delta f_2$ . . . $f_5 - \frac{1}{2}\Delta f_5$. These circuits are as little damped as possible and each of them permits the passage of frequencies f and $f - \Delta f$ with like efficiency. For the sake of clarity, only one complete circuit (corresponding to the first code signal) is shown in Fig. 2. Circuit 51 is connected in the middle to the grid of tube 56 whose plate

is fed by resistances 57 and connected across condenser 58 to the exciting windings 59 and 60 of the two resonant circuits 61 and 62. Circuit 61 has a resonance for a frequency slightly higher than f_1 and circuit 62 has a resonance for a frequency slightly lower than $f_1 - \Delta f_1$. The two circuits are differentially connected across rectifiers 63, 64 and resistances 65, 66 to polarized relay 67, exactly as is the case for the reception of the starting signal as above described. If the first code signal is a spacing signal, the frequency f_1 is received and the contact of relay 67 is open. If the signal is a marking signal, the frequency $f_1 - \Delta f_1$ is received and relay 67 closes its contact which is then connected to ground. The contact of relay 67 is connected to the contact terminals of springs 68, 69 which are actuated by cam 29. It will be understood that the circuit including tube 56, relays 67, 70 and 72 as well as cams 29 and 30 and the contacts operated thereby are only for the reception, storage and retransmission of the first impulse to the printer. There are four other identical circuits operated in the same manner for impulses, or frequencies two, three, four and five, controlled respectively from circuits 52, 53, 54 and 55 and each of these circuits has an individual pair of cams 29 and 30 associated therewith. Since these circuits are identical and operate in the same manner they have been omitted for the sake of clarity.

In the present embodiment, each cam 29 has associated with it a relay 70 and a relay 72. These relays are for the purpose of storing received impulses. Cams 29 which control the operation of relays 70 or 72 depending on which half cycle of shaft 25 is effective, all have the same angular position on shaft 25, because immediately on receipt of a start signal shaft 25 starts to move and either contact 71 or 81 closes an operating circuit for the group of relays 70 or 72 and immediately thereafter cams 29 close either contact 68 or 69 which causes either relay group 70 or 72 to store simultaneously any impulses registered by any operated relay 67 leaving the latter ready to register the simultaneously transmitted code impulses which follow immediately after the start impulse which initiated the operation just described. It should be noted that shaft 25 moves an appreciable distance before the transmission of the long start impulse has terminated, and therefore relays 67 are ready for a new code combination before the expiration of the start impulse.

The relays 70 when operated lock to battery from contact 71 when the apparatus is just beyond the position shown in Fig. 2 after a start pulse has been received and the shaft has turned a trifle from its normal position, and the relays of the group just referred to remain so locked until two further characters have been received, including the impulses for the character whose start impulse initiated the operation, during which time shaft 25 has made a complete revolution and then the cam again opens contacts 71 and releases the five relays 70 connected thereto making this group of relays ready to receive another group of impulses after the start impulse preceding this group has been received. Contact 81 operates in the same manner but 180 degrees after contact 71. This contact controls the locking circuit for a group of five relays 72, identical with relays 70 and operating in the same manner but 180 degrees, or one letter thereafter.

The respective cams 30 are mounted on shaft 75

25 in the same angular position, the effective length of the cams and their angular position on the shaft being such that the respective wires from contacts 74 or 80 leading to contacts 75, 5 76, 77, 78 and 79 of cam 24 which control the operation of magnet 21 when the latter is receiving selecting impulses will be simultaneously connected by the respective contacts 74 or 80 to individual ones of the relays in the group denoted by reference characters 70 or 72 depending on which half cycle of the shaft 25 is effective for this operation. The relay circuits will now be described in more detail. While the shaft 25 makes a half revolution upon rotation of shaft 22, spring 68 closes its contact and the registering relay 70 is connected to contact 68. If relay 67 has been operated, relay 70 is likewise operated from battery, contact 71, winding of relay 70, contact 68, armature of relay 67 to ground, and it becomes locked by its grounded tongue to battery at the spring contact 71 which is closed due to rotation of cam 28. At the end of the half revolution of shaft 25, contact 68 is open but relay 70 remains in the position where it finds itself as a result of the operation or non-operation of relay 67.

During the following half revolution, the contact of relay 67 is connected to a registering relay 72 of a second group of five relays, only one of which is shown by means of springs 69 disposed on the other side of cam 29. At the same time, the contact of relay 70 is connected by means of spring 74, which is operated by cam 30, to the first spring 75 of the distributor which in turn is actuated by cam 24. The indication registered by relay 70 is transmitted to the electromagnet 21 by means of contact 75 which is closed during the period of time when the reception of the first signal takes place in the telegraph receiver.

The invention operates as follows:

Synchronism of the transmitter and receiver motors is maintained by the well known start stop system. The transmitting station is arranged to send out an unusually long start impulse preceding the code combinations of each character which are sent out as a group of modulated frequencies simultaneously after the transmission of the start pulse. The relatively long start impulse and the still longer interval used to transmit simultaneously the frequencies corresponding to the selecting impulses permits the use of efficient filter arrangements at the receiving station that effectively eliminate parasitic frequencies.

The selecting frequencies are separated by filters and immediately on reception operate a combination of relays 67 of which there are five, according to the marking and spacing elements of the characters transmitted. A line signal having the characteristics just described is not adapted to operate any of the standard start stop printers, so accordingly, means are provided at the receiver to alter the received signals so that only a relatively short start signal is sent to the printer followed by suitably timed selecting impulses which are transmitted to the printer in succession.

In order to accomplish this purpose a storing arrangement is necessary, which in the present embodiment consists of two groups of storing relays 70 and 72 respectively. On receipt of the start impulse for a character, the combination as set up on relays 67 is transferred to relays 70 or 72 depending on the position of shaft

25. The operated relays of these sets remain locked in for substantially an entire revolution of shaft 25. On the receipt of a start impulse for a second character, cams 30, by means of contacts 14 or 80, depending on which half cycle of shaft 25 is effective, connects the contacts of any operated relays 70 or 12 to the wires extending from the contact levers of contacts 15, 16, 77, 78 and 79 of cam 24. The stationary contacts associated with the respective contact levers are connected to the windings 24 of the common start and selecting magnet of the printer. It will be understood that the printer shaft, not shown, and shaft 22 driven therefrom start to rotate when the start signal releases the printer clutch. As soon as the start magnet has released these shafts, contact 50 of cam 24 opens, irrespective of the length of the start signal, or whether it has terminated or not, and cam 24 proceeds to send to magnet 21 a series of impulses one after the other properly timed to operate the printer selecting mechanism according to the code combination for the first character. On receipt of a third start impulse, the letter is printed. The start impulse for a fourth character will cause the printing of the second character, and so on. All code combinations pass through the steps just described before the printing operation takes place. When a message is ended, it is customary to send a number of impulse combinations to cause the tape or paper web, in the case of a page printer to feed out. Two or more of these non-printing code combinations could be sent at the end of each message to clear the receiver of stored characters.

Although the present invention has been described in connection with a particular construction, many modifications and adaptations may be made without departing from the spirit and scope of my invention and it should therefore be noted that I do not intend to so limit the same.

I claim:

1. An alternating current start-stop printing telegraph system, comprising a group of continuously operating wave signal producers corresponding respectively to code signals and start signals, means for modulating and transmitting first a wave for a start signal and thereafter the waves all at one time for a given code character, so that each of said transmission is prolonged beyond single signal time but within substantially the time of code character transmission by signal sequence, in combination with a receiver and recorder comprising devices for translating the received signals pertaining to a given code character to a printed record thereof during a plurality of time periods of operation and means by which such devices are successively controlled by the start signals of succeeding code characters.

2. An alternating current start-stop printing telegraph system, comprising a group of continuously operating wave signal producers corresponding respectively to code signals and start signals, means for modulating and successively transmitting first a wave for a start signal and thereafter the waves all at one time for a given code character, so that each of said transmissions is prolonged beyond single signal time but within substantially the time of code character transmission by signal sequence, means for receiving and recording code character signals successively transmitted as aforesaid, comprising means including one or more sets of storing relays and responsive to reception of a start signal

to register simultaneously the code signals of the transmitted character corresponding to that start signal and to transfer said signals to a set of storing relays, and means responsive to start signals corresponding to subsequent characters for controlling operation of the printer to print the first mentioned character from the stored signals.

3. A telegraph system according to claim 1 wherein the wave producers continuously operate to produce wave frequencies assigned respectively to the component signals and means by which the waves so produced are transmitted in the absence of marking and starting signals.

10 4. An alternating current start-stop printing telegraph system, comprising a group of continuously operating wave signal producers corresponding respectively to code signals and start signals, means for modulating and transmitting first a wave for a start signal and thereafter the waves all at one time for a given code character, so that each of said transmissions is prolonged beyond single signal time but within substantially the time of code character transmission by signal sequence, said modulating means comprising devices for varying the frequency of the produced waves, in combination with a receiver and recorder comprising devices for translating the received signals pertaining to a given code character to a printed record thereof during a plurality of time periods of operation and means by which such devices are successively controlled by the start signals of succeeding code characters.

5. A telegraph system according to claim 1 wherein the code signal frequencies are contained within an octave.

6. A telegraph system according to claim 1 in which the code signal frequencies are chosen according to harmonically based numbers, a common basic frequency being adopted and the product of said basic frequency and each of the harmonic numbers giving the value of each code frequency.

7. A telegraph signal according to claim 1 in which the starting signal frequency is higher than the code signal frequencies.

8. A telegraph system according to claim 4 wherein the receiver translating devices comprise selective circuits of low damping and frequency discriminating circuits of high efficiency.

9. A telegraph system according to claim 4 wherein the receiver translating devices comprise selective circuits of low damping and electronic discharge amplitude limiters, whereby to reduce parasitic disturbances in transmission.

10. A telegraph system according to claim 4 wherein the receiver translating devices comprise selective circuits of low damping and electronic discharge amplitude limiters and wherein the frequency discriminating circuits are of high efficiency.

11. The method of code signalling by alternating currents wherein each code character consists of a predetermined number of code signals along with the start signal, which comprises continuously producing waves of low damping and of different frequencies corresponding to code and start signals, modulating said waves in accordance with code and start signal requirements by varying their frequencies, transmitting by radiation the modulated waves in a succession of a start signal followed by the code signals all at one time for a code character, each start signal and code signal occupying the time period allotted to a code character transmission, receiving the

transmitted waves, deriving therefrom the modulated signals by filtering, amplitude limiting and high frequency discrimination, translating and recording each of the code characters over successive time periods and controlling the initiation of operation in said time periods by successive start signals.

12. In a system of the character described for electrically transmitting messages by means of code signals, wherein each character of the message corresponds to a code symbol and each code symbol is composed of a predetermined number of code signals, a plurality of signal bars, the number of the latter being the same as the largest number of signals contained in any one symbol of the code, a contact associated with each of said bars, a plurality of frequency modulating circuits, each one of said circuits being connected to one of said contacts, operating means associated with and adapted to operate said bars to open and close said circuits, a radio transmitter, all said circuits being connected to said transmitter; an extra modulating circuit connected to said transmitter, make-and-break contacts, connecting means interconnecting said modulating circuits among each other and connecting the same to said make-and-break contacts, the latter being also connected to said extra modulating circuit, a control contact connected to the latter, and control means associated with said operating means and said control and make-and-break contacts, whereby, upon actuation of said operating means, said control means actuate said control and make-and-break contacts, to selectively open and close said circuits, while the respective bars simultaneously close said modulating circuits.

13. The system claimed in claim 12, in which said control means comprises a pair of cams for actuating said contacts.

14. In a printing telegraph system of the type described, means for simultaneously registering the code impulses of each transmitted character, means for printing said characters, means for transmitting a start impulse for each operation of said printing means, and means for delaying each successive operation of said printing means pending operation of said start impulse transmitting means.

15. In a printing telegraph system of the type described, means for simultaneously registering the code elements of a transmitted character, a set of storing relays, means responsive to the start signal of the next following character for transferring the code elements of the first mentioned character to said set of storing relays thereby making said registering means available to register the code elements of said next following character, a start stop printer, and means responsive to the start signal preceding the transmission of the code elements of a third character for transferring the code elements of the first mentioned character one at a time from said storing relays to said printer, thereby causing the printing of the first mentioned character after the printing operation has been initiated by the start signal of the third character.

16. In a printing telegraph system of the start stop type, means for receiving a starting signal of a predetermined frequency followed by a plurality of different frequencies simultaneously transmitted corresponding to the marking and spacing units of a code character, a printer having a single magnet responsive to start signals followed by successively transmitted selecting impulses, a plurality of registering relays, means

for separating said different frequencies and simultaneously operating a combination of said relays thereby, whereby said relays are positioned in accordance with the marking and spacing units of the code character, means responsive to the receipt of a second start impulse for transferring the code elements registered by said relays to a set of storing relays, and means responsive to a third start signal preceding the transmission of the frequencies for a third character for transmitting the impulses of the first mentioned character one at a time to said printer magnet after said magnet has been actuated by said third start signal whereby said printer prints the first mentioned character.

17. In a printing telegraph system of the start stop type, means for receiving a starting signal of a predetermined frequency followed by a plurality of different frequencies simultaneously transmitted corresponding to the code elements of a character, a printer having a single magnet responsive to start signals followed by successively transmitted selecting impulses, registering relay means, a plurality of filter means each connected to a relay of said relay means, said filter means being adapted to separate the simultaneously transmitted frequencies and pass the respective frequencies to predetermined ones of said relays whereby the latter are operated in combinations corresponding to the code elements of the received character, a plurality of storing relays, means responsive to the receipt of a second start frequency preceding the frequencies corresponding to the code elements of a second character for transferring the code elements of the first mentioned character recorded by said registering relays to a set of corresponding storing relays, and means operable in response to a third start signal preceding the reception of the frequencies for a third character for transmitting impulses one at a time from the operated ones of said storing relays to said printer magnet whereby said printer prints the first mentioned character.

18. A telegraph system according to claim 17 wherein said means for transmitting impulses one at a time to said printer comprises a distributor.

19. A telegraph system as claimed in claim 17 wherein said means for transmitting impulses one at a time to said printer comprises a distributor having a rotary shaft driven from the printer power shaft.

20. A telegraph system as claimed in claim 17 wherein said means for transmitting impulses one at a time to said printer comprises a distributor having a rotary shaft driven from and at the same rate as the printer power shaft, and wherein the means for transferring the code combinations from the registering relays to the storing relays comprises a second distributor having a rotary shaft driven from the printer power shaft.

21. A telegraph system as claimed in claim 17 wherein said storing relays comprise two independent sets of storing relays, a second distributor having a rotary shaft driven from said printer power shaft at one half the speed of said power shaft, said second distributor being adapted to connect the respective sets of storing relays to the contacts of said registering relays alternately, whereby each storing relay set stores only alternate letters.

22. A telegraph system as claimed in claim 17 wherein said means for transmitting impulses one at a time to said printer comprises a distributor

13

having a rotary shaft driven from and at the same rate as the printer power shaft, and wherein said storing relays comprise two independent sets of storing relays, a second distributor having a rotary shaft driven from said printer power shaft at one half the speed of said power shaft, said second distributor being adapted to connect the respective sets of storing relays to the contacts of said registering relays alternately, whereby each storing relay set stores only alternate letters, and circuit means controlled by said second distributor for connecting the contacts of the respective sets of storing relays alternately to the contacts of the first mentioned distributor.

23. A telegraph system as claimed in claim 17 wherein said storing relays comprise two independent sets of storing relays, and wherein a second distributor having a rotary shaft is driven from the printer power shaft at one half the speed of said power shaft, said second distributor having contacts adapted to connect the respective sets of storing relays to the contacts of said registering relays alternately, one set being thus

14

connected during each half cycle of the second distributor shaft, whereby each storing relay set stores only alternately transmitted letters, a locking circuit for each set of storing relays and means for opening the locking circuit of the respective sets alternately comprising contact means in each locking circuit spaced 180 degrees apart about the second distributor shaft and a cam for opening said contact means disposed on the last mentioned shaft.
